UNITED STATES PATENT OFFICE.

EDWARD L. WALKER, OF TWIN GROVE, WISCONSIN.

IMPROVEMENT IN HAY-CARRIERS.

Specification forming part of Letters Patent No. 177,901, dated May 23, 1876; application filed April 7, 1876.

To all whom it may concern:

Be it known that I, EDWARD L. WALKER, of Twin Grove, county of Green and State of Wisconsin, have invented a Hay-Carrier, of which the following is a specification:

The object of my invention is to elevate the hay perpendicularly from the load, and, after being raised as high as desired, then to convey it any desired distance horizontally, using an ordinary horse hay-fork to lift the hay.

In the accompanying drawing, Figures 1 and 2, A A represent two pieces of scantling, which are secured to the rafters in a barn, or to the poles of a derrick when used for stacking, either with bolts or cleats nailed thereto, allowing sufficient space between the scantlings for the carrier to pass.

The carrier consists of a sheaf-case, B, which has projections or flanges a a on both sides, to slide on the scantlings, and also projection b, to which the pendent catch C is attached, and projection c', to which the lever D is attached. The pendent catch C is so hung as to have a lateral motion, and susceptible of being shoved aside laterally by any pressure that may be brought against it.

The lever D is attached to the sheaf-case B at the point c' loosely, so that it may be operated up or down, and so arranged that the long or curved end will overbalance the short end, which is set against a catch, d, fastened on the lower side of the scantling.

The pendent catch C has a pin, e, which, when the carrier is drawn backward, will strike and slide on the face of a guard, f, fastened to the scantling, which will produce in the pendent catch C a side oscillation.

The hoisting-rope E E has its load to be elevated attached at g, and, just above this point, has a round plate, F, bolted or otherwise securely fastened to the rope, and the elevating power is attached to the hoisting-rope at h, or is simply a continuation of the rope to such point where the power can be hitched to it.

There is also fastened to the back end of the carrier a cord, i, which passes over a pulley, J, and has a weight, K, attached to it.

Now, when the horse or elevating power causes the load to move upward the lever D

sets firmly against the catch d, and prevents the carrier from moving forward. When the plate f strikes and slides against the side of the pendent catch C the said catch is moved aside, allowing the plate to pass on; but as soon as the plate F has passed the catch C the catch immediately drops back, and prevents the plate and the load from dropping down. This object accomplished, it is then safe to unlatch the carrier, so that it can move forward, and this is done by the draft continuing, and when the plate F strikes the lever or latch D it unlatches the carrier at d, and then, the draft still continuing, the carrier with its pendent load is drawn to any desired distance, where the load may be discharged, and while the load is thus going forward the cord i, with its weight K attached, is drawn upward; but when the load of hay or other material is dropped off, then the cord i, by means of the weight K, will have sufficient force to return the carrier to the place from whence it started, and the pin e, by sliding on the guard f, will drive the pendent catch C away from under the plate F, and hence allow the hay-fork or other hoisting-instrument either to drop or be drawn down by means of a cord attached to it.

It must be noticed that the lever D must have sufficient play, so that the pin e may move forward a sufficient distance to liberate the catch C before the lever D is set against the catch d, in order that the catch C may drop under and catch the plate F.

What I claim as my invention is—

1. In a hay-carrier, a pendent catch, being so arranged that it may be shoved aside by a plate or fastening, bolted or otherwise secured to the hoisting-rope, and operating substantially as described.

2. The combination of the sheaf-case B, pendent catch C, and lever D, in the manner and for the purposes specified, and operating with the catch d and guard f, substantially as described.

EDWARD L. WALKER.
